UNITED STATES PATENT OFFICE

GEORGE NORTON, OF BIRMINGHAM, ENGLAND

COAL BREAKER

Application filed November 16, 1928, Serial No. 319,940, and in Great Britain December 2, 1927.

This invention relates to machines for breaking coal or other material of the type embodying primary and secondary picks which are moved up and down, the coal or other material being carried on a conveyor formed of steel plates hinged together to provide a more or less smooth table which travels under the picks whereby the coal is pierced and broken up into marketable sizes. This enables the larger coal from the primary set of picks to be conveyed to the secondary set of picks in the ordinary way.

According to this invention, a machine for breaking coal or other material has a conveyor belt formed of a series of grids or open-meshed members jointed or linked together, whereby such material as is already broken into size by the primary series of picks may fall through the grids or open-meshed members and so avoid further breakage by passing to the secondary picks.

In conjunction with the grids or open-meshed members is a deflector plate or plates which is or are disposed below the forward or conveying section of the conveyor belt for preventing the broken material from falling on to the return side of the conveyor belt.

The invention is described with reference to the accompanying drawings illustrating a preferred embodiment of the invention.

Fig. 1 is a longitudinal section of a machine constructed according to this invention.

Fig. 2 shows a half plan of the machine, and

Fig. 3 is a transverse section on line *a*, *a*, of Fig. 1.

In the improved machine, the main driving shaft 1 is mounted upon a suitable foundation and a connecting rod 2 couples the crank shaft 40 with a beam 3 swinging on the axis 4. The beam 3 carries on its fore end the primary picks 5 and on its aft end the secondary picks 6. Each series of picks are dependently carried from the beam 3 and the secondary picks descend through apertures 7 of take-off plates 8 on being brought into action alternately. Located below these picks is a conveyor belt consisting of a series of grids or open-meshed members 9 jointed together at 10 having apertures 11 of square shape, as shown, but these

apertures may be varied as circumstances require. The conveyor belt laterally extends from side to side of the machine and is driven by means of four-sided or other polygonal drums 12 secured to shafts 13 and operated from the main shaft 1 or by any other suitable means.

The effect of adopting drums with a small number of flat sides is to give the conveyor belt a halting or faltering motion of varying speed. These are arranged so that at the moment when the primary picks descend, the conveyor is at its "halt" period and the section of the conveyor immediately under the picks is then in its lowest position and is resting on, or nearly so, upon a set of girders 14 which serve to absorb the impact of the picks and relieve concussion from the conveyor belt. Deflector plates 15 are arranged below the forward or conveying section of the conveyor belt, but above the return section of the same, said plates sloping downwardly in an outward lateral direction from the central part of the machine so as to deflect the broken coal falling through the apertures 11 away from the return section of the conveyor belt.

In practice, motion is imparted by the driving shaft 1 to the connecting rod 2 by which an oscillating motion is given to the beam 3 and hence an alternate striking movement by the two groups of picks. The rotary motion of the driving shaft 1 likewise imparts rotary motion to the drums 12 and a surging movement is imparted to the conveyor belt. The coal travelling down a chute 16 falls on to the conveyor belt, the movement of which brings the coal immediately under the primary picks 5, where during a period of dwell, the first breaking takes place. If the first breaking reduces the coal to the required size, such coal will pass through the openings in the conveyor belt and not be conveyed to the secondary picks 6. The conveyor belt by its continued movement takes the larger coal under the secondary picks where the coal is reduced to the required size.

After the final breaking, all the remaining "small" will either fall through the apertures in the conveyor belt, or will be delivered.

ered over the end of the conveyor belt and the whole of the broken coals then collected in a receiving hopper 17 for ultimate discharge on to a sizing screen, or into other hoppers as may be required.

The invention is applicable to primary and secondary picks which are moved up and down simultaneously instead of alternately.

What I claim is:—

- 10 1. In a coal breaking or like machine having primary and secondary picks movable up and down, a conveyor belt formed with a series of grids or open-meshed members jointed or linked together and movable under the picks and a deflector plate or plates disposed below the forward or conveying section of the conveyor belt so as to deflect the broken coal falling through the forward or conveying section away from the return section.
- 20 2. In a coal breaking or like machine having primary and secondary picks movable up and down, a conveyor belt having a series of grids or apertured members hinged together through which the material is allowed to fall after breaking by the primary picks and the larger material carried for operation by the secondary picks for delivery to a hopper, a deflector plate interposed between the forward section of the conveyor belt and the return section of the same, and polygonal drums over which the conveyor belt is arranged for giving a surging movement to said belt.
- 30 3. In a coal breaking or like machine having primary and secondary picks movable up and down, a conveyor belt having a series of grids or apertured members jointed or linked together and movable under the picks, deflector plates arranged below the forward or conveying section of the conveyor belt and above the return section of the same, said plates sloping downwardly in an outward direction from the central part of the machine so as to deflect the broken coal falling through the forward section of the belt away from the return section of the same, a chute to feed coal on to the conveyor belt and a receiving hopper for ultimate discharge.
- 40 4. In a coal breaking or like machine, a swinging beam mounted on an intermediate axis and carrying on its forward end the primary picks and on its aft end the secondary picks, a conveyor belt having a series of grids or apertured members hinged together and located below the primary and secondary picks, square-sided or other polygonal drums remotely positioned on which the belt is carried, outwardly and laterally sloping deflector plates arranged below the conveying section of the belt but above the return section of the same, and means for imparting motion to the conveyor belt.
- 50 5. In testimony whereof, I have signed my name to this specification at Birmingham, England, this 26th day of October, 1928.
- 60 65

GEORGE NORTON.
